INVENTOR.

UNITED STATES PATENT OFFICE.

LOUIS J. GOLDBERG, OF NEW YORK, N. Y.

MAT.

Application filed June 20, 1922. Serial No. 569,641.

To all whom it may concern:

Be it known that I, LOUIS J. GOLDBERG, a citizen of the United States, residing at New York, in the county of New York and State 5 of New York, have invented new and useful Improvements in Mats, of which the following is a specification.

In carrying out the present invention it is my purpose to provide a mat for use on the 10 running boards of motor vehicles, by means of which dirt may be removed from the shoes of persons entering the vehicle.

It is also my purpose to provide a mat of the class described which will embrace the 15 desired features of simplicity, efficiency and durability, which may be readily and quickly attached to the running board and which will be constructed in such manner as to prevent a foot of a person stepping into the vehicle from striking the apron that usually 20 extends from the body to the running board.

A further object of my invention is the provision of a mat with an opening in the center thereof in which a section bearing a 25 letter or other indicia may be inserted and removed, and whereby such section may be securely and effectively held in place.

With the above recited objects in view, and others of a like nature, the invention resides 30 in the construction, combination and arrangement of parts set forth in and falling within the scope of the appended claims.

In the accompanying drawings:

Figure 1 is a plan view of a mat constructed 35 in accordance with my invention.

Figure 2 is a sectional view on the line 2—2 of Figure 1.

Figure 3 is a cross sectional view on the line 3—3 of Figure 1.

Referring now to the drawings in detail, 40 1 designates a mat preferably constructed of metal and substantially rectangular in outline, as clearly shown in Figure 1 of the drawings. This mat at the respective corners 45 thereof is formed with openings 2 through which screws or other fastening devices may pass in order to secure the mat to the running board of the vehicle. The inner edge of the mat, that is, the edge adjacent to the apron, 50 is formed with an upwardly extending outwardly curved flange 3 that acts to protect the apron from contact with the foot of the person stepping into the vehicle.

In accordance with my invention the center 55 of the mat is formed with a substantially

diamond-shaped opening 4 having its longest dimension, in the present instance, extending longitudinally of the mat and a shorter dimension extending across the mat, as shown in Figure 1. The under surface 60 of the mat contiguous to the walls of the diamond-like opening 4 is rabbeted, as at 5, and seated in the rabbeted portion 5 are edges of a diamond-shaped section 6 bearing a letter 7 or other indicia. This 65 removable section 6 is of less thickness than the thickness of the body of the mat 1, so that the lower surface of the initial bearing section will be flush with the under surface of the mat 1, as shown in Figures 2 and 3 of the 70 drawings, thereby enabling the section 6 to be maintained in proper position in the opening 4 by the fastening devices that hold the mat to the running board.

In practice, the upper surface of the mat 1 75 is roughened, as at 8, so as to present a cleaning surface, and the body of the mat 1 may be composed of metal or other material, while the removable section 6 may also be formed of a desired material and suitably ornamented, if desired.

While I have herein shown and described one preferred form of my invention by way of illustration, I wish it to be understood that I do not limit or confine myself to the 85 precise details of construction herein shown and described, as modifications and variations may be made within the scope of the claim and without departing from the spirit of my invention. For instance, the longest 90 dimension of the diamond-shaped opening in the body of the mat may extend transversely of the mat and the shape of the removable section and also the shape of the opening in which the removable section is seated may be 95 changed to any desired contour, such, for example, as square, oblong, round, octagon, etc. It is, of course, understood that the removable section may be equipped with the names of cars, insignias, designs or any other 100 indicia.

Having thus described the invention, what I claim as new, is:—

A mat for the running boards of motor vehicles, comprising a body portion formed 105 with an opening at its center, and having its under surface rabbeted continuously to the walls of said opening and a removable section in the opening having its edges seated in the rabbeted portions of the body and of 110

a thickness less than the corresponding dimension of the body, whereby the lower surface of the removable section will lie flush with the corresponding surface of the body 5 of the mat and whereby the upper surface of the removable section will lie beneath the corresponding surface of the body of the mat,

the last named surface of the removable section having suitable indicia formed centrally thereon, the upper surface of this indicia 10 being flush with the upper surface of the mat.

In testimony whereof I affix my signature.

LOUIS J. GOLDBERG.
